UNITED STATES PATENT OFFICE.

RALPH M. WESTON, OF SOUTHBRIDGE, MASSACHUSETTS.

MACHINE FOR MAKING TEMPLES FOR SPECTACLES.

1,054,631.

Specification of Letters Patent. Patented Feb. 25, 1913.

Application filed June 29, 1911. Serial No. 636,064.

To all whom it may concern:

Be it known that I, RALPH M. WESTON, a citizen of the United States, residing at Southbridge, in the county of Worcester and 5 State of Massachusetts, have invented a new and useful Machine for Making Temples for Spectacles, of which the following is a specification.

This invention relates to a machine particularly adapted for making temples for 10 spectacles but capable of use in any case in which a comparatively long, thin blank like a wire is reduced and expanded and provided with an enlarged end.

15 The principal objects of the invention are to provide simple and convenient means for holding the blanks; to provide means for taking the blanks therefrom and feeding them lengthwise into contact with the metal 20 working tools; to provide for operating said feeding means so as to alternately advance and withdraw the blank; to provide means whereby when the blank has been fed through to a certain point, the feed will be 25 stopped; and especially to provide an improved form of rotary tool-holding device capable of acting on the blank by means of a plurality of pairs of radially reciprocable jaws, each movable in a very simple way 30 into and out of working position.

The invention also involves improvements in details of construction as will appear hereinafter.

Reference is to be had to the accompanying 35 drawings in which—

Figure 1 is a side view of a machine constructed in accordance with the principles of this invention. Fig. 2 is a longitudinal sectional view on enlarged scale along the 40 center of the die holding elements and their operating devices. Fig. 3 is a sectional view on the line 3—3 of Fig. 2. Fig. 4 is a sectional view on the line 4—4 of Fig. 2; Fig. 5 is an end view of the parts shown in 45 Fig. 2. Fig. 6 is a similar view of a detail. Figs. 7, 8, 9, 10 and 11 are diagrammatic views showing the progress of the finishing operation as performed by this machine. Fig. 12 is a central longitudinal 50 sectional view of the feeding device. Fig. 13 is a plan thereof. Fig. 14 is a transverse sectional view of the feeding device on the line 14—14 of Fig. 12. Fig. 15 is a plan of the magazine, and Fig. 16 is a side view of 55 the same.

The invention is shown in the form of a machine embodying a frame 8 having a reservoir 9 for receiving oil and shavings from the work. The frame has a bearing 10 for a main hollow spindle 11, which is provided 60 with a pulley 12 for receiving power from any desired source.

Concentric with the spindle is a stationary head 13 having a face-plate 14 thereon and provided with a roller cage 15 for receiving a circular series of rollers 16. The face-plate covers the front ends of the rollers and they project inwardly slightly beyond the inner boundary of the cage. The head is provided with a recess in which is 65 located an enlargement 17 of the spindle. Arranged to slide in radial slots in this enlargement are a series of dogs 18. Four of these are shown in the drawings. Each dog is located behind a dog plate 19 which has 70 slots 20 through which it is held by screws so that the dog can move radially but is kept in guides. For the same purpose each dog plate is provided with a pin 21 adapted to enter a recess 22 in the dog. These dogs 75 are provided with rounded surfaces at their ends which are engaged by the rollers during the rotation of the spindle so as to cause the dogs to reciprocate in the slots. These dogs, it will be observed, are mounted in 80 pairs, the two dogs of each pair being arranged opposite each other, and as the rollers are mounted in regular order and diametrically opposite each other, it will be 85 seen that the two dogs of one pair will be forced inwardly simultaneously.

Adjacent to the dogs of each pair are sets of pivoted wedges 23 and 24. These wedges are adapted to operate two wedge blocks 25 and 26 which in turn push in the 95 dies 27 and 28.

It will be observed that the wedges 23 and 24 are arranged in pairs like the dogs and dies. These wedges are reciprocable, each pair being movable independently of 100 the others. The two pairs of wedges are operated by similar pairs of slides 30 and 31 movable longitudinally in slots along the spindle 11. It will be observed that the pushing of either pair of wedges out to the 105 right in Fig. 2 will force the corresponding pair of dies radially inwardly into operative position. These slides are operated by a pair of collars 33 and 34, respectively, one for the breaking down and the other for the 110

finishing dies 24. These are secured to the slides and are provided with grooves in which work operating fingers 35 and 36 which are mounted on heads 37 slidably mounted on a guide 38. Each head has a roller 39. These heads are operated from a shaft 40, worm wheel 41, cam shaft 42, and two cams 43, one for each roller 39. These cams positively force the slides, and consequently the clutches, inwardly to the right but they are drawn back yieldingly by springs 44. The cams are not shown in detail but they are so arranged that when one pair of wedges is in working position, the other is drawn back so as to bring the dies back to inoperative position.

In operation the work is received between the dies as will be explained hereinafter. The feeding of the wire blanks to these dies according to the machine illustrated will now be described.

On the shaft 42 are located a pair of cams 45 and 46 shown as mounted on a single disk. The cam 45 periodically operates a roller bearing arm 47 on a short shaft 48 and oscillates a gear segment 49 on this shaft. This gear segment meshes with a pinion 50 loosely mounted on a shaft 51. This shaft is supported in bearings on a frame 52 located on a base 53 which constitute the magazine frame. The shaft is provided with a collar thereon having a spring-pressed pin 54 engaging a ratchet tooth or teeth on a head 55 on the pinion 50. This is for the purpose of permitting the pinion to rotate the shaft in one direction and to rotate back without rotating the shaft. To prevent rotation of the shaft under the latter circumstances and prevent its rotating too far in the forward direction, an adjustable friction screw 56 is used.

On the shaft 51 is a feed-screw 57 located between guides 58. The blanks A are intended to be placed on this screw crosswise and the intermittent rotation of the shaft 51 feeds the blanks forward laterally and keeps one end against one of the guides 58. For each rotation of the shaft 42 the shaft 51 is rotated one revolution and carries a blank substantially a distance equal to its own diameter.

The cam 46 operates a roller 60 on a reciprocating elevator slide 61 which moves up and down past the end of the guides. This slide is provided with a transverse notch 62 for receiving one blank at a time from the feed screw. It will be seen therefore, that on each rotation of the shaft 42 a blank is fed into the notch 62, and immediately thereafter the slide is raised so as to bring the blank up in position to be fed forward in a manner that will be described hereinafter.

Mounted on the shaft 42 is a rotary drum 70 having a cam groove 71 therein. Above

this on a frame 72 is supported a slide 73. This slide is provided with a fixed axial pin 74 on which is a fixed collar 75 against which rests an extension 76 on the slide. This extension is provided with a pin 77 and roller 78, the roller entering the groove 71. A spring 79 normally holds the extension 76 against the collar 75 so that the positive motion of the roller, forward or back will also move the slide 73 except when the spring 79 is caused to contract, as will be explained hereinafter.

Mounted on the slide 73 is a transverse shaft 80 having a hand wheel 81 for turning it and provided with an elliptical operating piece 82. On this shaft is an arm 83 for operating it and on the drum 70 are pins 84 and 85 for operating this member as the drum rotates. The contact of this arm 83 with the pin 84 turns the shaft into the position shown in the drawing, in which the elliptical member 82 is arranged crosswise. Its contact with the other pin swings it around ninety degrees into a position in which it is arranged longitudinally. In the latter position it engages a plunger 86 and pushes it forward. This plunger bears on the end of an adjustable rod 87 moving with it on which is a head 88 having oppositely slanting surface. The rod is provided with a spring 90 held by nuts 91 located in a recess in the slide. Movably mounted on this rod is a slide 92, pivotally mounted on which are a pair of gripping jaws 93. The head 88 engages their inner ends and when pulled back by the spring, holds the jaws closed. When the elliptical member 82 is turned to the longitudinal position it forces the head 88 to the left in the drawings and releases the jaws so that they cannot grip an article at their ends.

Between the jaws is a central longitudinal pin 94 adjustably mounted on a stud 95 secured in the plunger 92, and secured in adjusted position by a screw 96. This pin determines the position of a blank in the jaws. On the motion of this feeding device the jaws grip a blank held in the notch 62, said notch being in elevated position, to feed it forward to a tool mounted on the spindle 11.

When a piece of work has been operated upon throughout its length, it is brought into the central passage in a bushing 99 on the end of the spindle and then it engages the end of a rod 100 in the passage in the spindle. This rod slides through a bushing 101 and is provided with a head 102. When it is forced out by the work it engages a spring 103 which is held by a screw 104. This causes the spring to make a contact with the end of an adjustable screw 105. These screws are supported by a bracket 106 adjustably mounted on the frame by means of screw 107. The screw 105 is ad-

justable as well as the bracket so that the device can be arranged with this electrical contact to be made at the proper time for operation with work of any desired length.

5 When the electrical contact is made it causes the current to flow through an electromagnet 108. This attracts an armature 109 and disconnects a notch in the latter from a fixed hook 110 which normally held 10 the armature opposite the core of the magnet in opposition to the action of a spring 111. Now the spring acting on a bell-crank 112 pulls the armature over (toward the bottom of the sheet in Fig. 14) and swings 15 the bell-crank, thus pushing in a plate 113. This plate has a cam 114 connected therewith which is pivoted on a stud 115. It engages a plate 116 adjustable on the slide 73 and binds the latter so that it is no longer 20 capable of moving. Now the further rotation of the drum 70 simply acts to move the extension 76 in opposition to, or with, the spring 79 without transmitting its motion to the slide 73 so that the making of this 25 electrical connection stops the feed, although it does not stop the main shaft. The cam 17 restores the latch.

In the description of the elements so far given, the shape of the cams is not described 30 in detail and it is not necessary to specify their particular forms and relative arrangements. It will be sufficient to say that they are so designed as to cause the mechanism to move in accordance with the diagrammatic 35 Figs. 7 to 11, inclusive. The operation of the machine will be described broadly, therefore, in view of these figures.

Fig. 7 shows the blank A in the form in which it is supplied to the machine, gripped 40 at one end by the jaws 93 and forced between the breaking down dies 27 until its end enters the end of the passage in the bushing 99. This centers the work. Now one of the cams 43 acts to force the collar 45 33 to the right and with the wedges 23. This brings the dies 27 into engagement with the work so that as the spindle rotates, the dogs alternately come into and out of contact with the rollers 16 and act on the blank 50 to reduce the diameter thereof. The work is fed backwardly for a time, as shown in Fig. 8, until the portion A' engaging these dies 27 in Fig. 7 is reduced and lengthened, as shown in Fig. 8. Then the work moves 55 back again in the opposite direction, as indicated in Fig. 9, until it reaches its original position, as shown in Fig. 7. This completes the work of the breaking down dies and at this time the collar 33 is drawn back to 60 the left and the collar 34 moved to the right by their respective springs and cams so that the finishing dies 28 are brought into engagement with the work. Then the work is drawn back again to the right until it 65 reaches the position shown in Fig. 10 and

finally is drawn back to the left until it is pushed all the way through, Fig. 11 shows this last operation partially completed. At the end of this operation the end of the work; that is, in the present case a temple, 70 engages the rod 100, makes the electrical connection and stops the feed. It will be seen, therefore, that the various operations required for forming an article with a reduced shank and an enlarged end, as for 75 example, an eye-glass temple, is made by this machine in a very efficient and expeditious manner, the temple being securely held at all times and the entire operation of the machine being automatic.

While I have illustrated and described a preferred embodiment of the invention, I am aware that many modifications can be made in each of the several parts thereof without departing from the scope of the invention as expressed in the claims. Therefore, I do not wish to be limited to all of the details of construction herein shown and described, but

What I do claim is:—

1. In a device of the character described, the combination of a rotary spindle, a stationary head concentric therewith, a plurality of sets of radially movable dies carried by the spindle, dogs movable radially 90 for operating said dies, means on the head for operating the dogs intermittently as the spindle rotates, a series of wedges for transmitting motion from the dogs to the dies, and means for moving one set of wedges longitudinally into operative position and simultaneously moving another set of wedges out of operative position.

2. In a device of the character described, the combination of a rotary spindle, a spindle head concentric therewith, a plurality of sets of dies carried by the spindle, an equal number of dogs for operating said dies, means on the head for operating the dogs as the spindle rotates, a series of wedges for transmitting motion from the dogs to the dies, and means for moving said wedges into and out of operative position, said dies having surfaces thereon adapted to move the inoperative dies back out of the way.

3. In a device of the character described, the combination of a reciprocating slide, a rotary drum for reciprocating it, a pair of jaws on said slide, and means operated by said drum during its rotation for causing 110 said jaws to open and close.

4. In a device of the character described, the combination of a reciprocating slide, a rotary element, means connected with the rotary element for reciprocating the slide, a pair of jaws on the slide, and means on the rotary element for causing said jaws alternately to close.

5. In a device of the character described, the combination of a reciprocating slide, a

- pin extending therefrom, a spring on the pin, an extension of the slide located on the pin and normally held at a distance from the slide by the spring, means for reciprocating said extension, a plunger on the slide having a head thereon provided with oppositely slanting sides, a pair of jaws on the slide in position for said head to engage them, whereby when the head is drawn back so that the broader portion thereof will engage the jaws said jaws will be closed, a spring for normally forcing said slide back, and means for positively forcing said slide forward to open the jaws as the slide reciprocates.
15. 6. In a device of the character described, the combination of a reciprocatory slide, an extension of the slide, yieldingly held at a distance from the slide, means for reciprocating said extension, a rod on the slide having a head thereon provided with converging sides, a pair of jaws on the slide in position for said head to operate them, whereby when the head is moved to one extreme position said jaws will be closed, a spring for normally forcing said rod back, and means for positively forcing said rod forward to open the jaws comprising a transverse shaft, an elliptical cam on said shaft in position to engage said rod when arranged longitudinally, an arm on the shaft, and a movable member for reciprocating the slide having means for turning said arm and shaft.
20. 7. In a feeding device, the combination of a magazine comprising a guide, a screw parallel with the guide, means for intermittently rotating said screw, whereby blanks located in the threads thereof will be fed forward one end of the screw, an elevating means at the end of the screw for receiving blanks therefrom, a gear on said screw, a segment for operating the gear, a ratchet for connecting the gear with the screw, and means for oscillating said segment.
25. 8. In a machine of the character described, the combination of a rotary spindle, a plurality of dies mounted on the spindle and movable thereon, dogs in line with the dies, sets of wedges between the dogs and dies, slides longitudinally movable on the spindle and engaging the wedges, and means for reciprocating the slides whereby one set of wedges are removed and another set are engaged.
30. 9. In a machine of the character described, the combination of a rotary spindle having a plurality of dies mounted thereon, opposite sets of slides reciprocably mounted in the spindle and means for reciprocating the sets of slides simultaneously in opposite directions.
35. 10. In a machine of the character described, the combination of a rotary spindle having a plurality of dies mounted thereon, opposite sets of slides mounted in the spindle, collars securing each set of slides, and means for simultaneously driving the collars in opposite directions.
40. 11. In a machine of the character described, in combination with a fixed head having a roller cage thereon, a single rotary spindle having a plurality of dogs and dies of equal number mounted and movable thereon, the dogs being arranged in sets, means for rotating the spindle and transmitting motion through the dogs to the dies and means for simultaneously releasing one set of dogs and engaging the other.
45. 12. In a machine of the character described, the combination of a reciprocal work slide, an extension of said slide resiliently separated from the main slide, a projection on the extension, a cam drum engaging the projection, and means to rotate the drum and reciprocate the slide.
50. 13. In a machine of the character described, the combination of a reciprocating work slide having operable jaws, a cam on the slide, a drum, and means on the drum adapted to engage the cam and open the jaws.
55. 14. In a machine of the character described, the combination of a reciprocating work slide having operable jaws, a cam on the slide, a drum, means on the drum adapted to engage the cam and a spring to close the jaws after the pin on the drum disengages the cam.
60. 15. In a machine of the character described, the combination of a reciprocating work slide having operable jaws, a cam on the slide, a rod engaging the cam and the jaws, a revolving drum, and means on the drum adapted to engage the cam to open the jaws at determined periods.
65. 16. In a machine of the character described, the combination of a magazine feed table comprising a single revolving screw, guides adjacent the screw, threads on the screw adapted to contain the stock to be transferred thereby, an elevator adapted to remove a single piece of stock from the threads and a cam adapted to operate the elevator.
70. 17. In a machine of the character described, the combination of a magazine feed table comprising a single revolving screw, guides adjacent the screw, threads on the screw adapted to contain the stock to be transferred thereby, an elevator adapted to remove a single piece of stock from the threads and a cam for releasing the elevator means to return it to its normal position below the line of the stock in the screw.
75. 18. In a machine of the character described, the combination of a magazine feed table comprising a single revolving screw, guides adjacent the screw, threads on the screw adapted to contain stock to be trans-

ferred thereby and an elevator adapted to remove each successive blank from the threads.

19. In a machine of the character described, the combination of a magazine feed table comprising a single revolving screw, guides adjacent the screw, threads on the screw adapted to contain stock to be transferred thereby an elevator adapted to 10 move each successive blank from the threads and means for revolving the screw intermittently in one direction, whereby the stock will be successively conveyed to the elevator.

15 20. In a machine of the character described, the combination with a revolving swaging head carried on a single spindle and journaled within a fixed head, a plurality of dies contained within the swaging 20 head, a separately driven shaft operating

to change the dies in the head at suitable intervals, work feeding means, a drum on the shaft directly operating the work feeding means, work grasping means, means on the drum adapted to operate the work 25 grasping means, a magazine supply operated by the shaft, an elevator operated by the shaft to position the work in the grasping means, an electrical stop gear to positively stop the advance of the feeding means when 30 the work has reached a predetermined length, and means for releasing the stop gear.

In testimony whereof I have hereunto set my hand, in the presence of two subscribing 35 witnesses.

RALPH M. WESTON.
